UNITED STATES PATENT OFFICE.

LEON KLEIN, OF PHILADELPHIA, PENNSYLVANIA, ASSIGNOR TO LEHIGH SILK HOSIERY MILLS, INC., OF PHILADELPHIA, PENNSYLVANIA, A CORPORATION OF NEW YORK.

INDICATING DEVICE FOR POSITIONING STOCKING-BLANKS.

1,176,298.

Specification of Letters Patent. Patented Mar. 21, 1916.

Application filed July 22, 1915. Serial No. 41,359.

To all whom it may concern:

Be it known that I, LEON KLEIN, a citizen of the United States, residing at Philadelphia, in the county of Philadelphia and 5 State of Pennsylvania, have invented certain new and useful Improvements in Indicating Devices for Positioning Stocking-Blanks, of which the following is a specification.

- 10 In embroidering stocking blanks on pantograph embroidery machines, the blanks are stretched upon suitable frames which are then placed in the embroidery machine to hold the different parts of the plurality 15 of blanks in proper relation to the plurality of embroidery mechanisms which are all controlled by a single, hand-operated pantograph device, in accordance with a prescribed embroidery design.
- 20 When designs which bear a particular relation to the lateral heel seams and the adjacent reinforced parts of the stocking blanks are to be embroidered on the blanks, it has been found quite difficult to stretch 25 the several blanks on the several frames so that the lateral heel seams and the adjacent reinforced parts of the blanks shall bear a uniform relation to the frames on which they are stretched, such uniform relation being necessary to cause the embroidery mechanisms to embroider the design on the several blanks in the same relation to their lateral heel seams and their adjacent reinforced parts. This is especially true when 35 clock designs are embroidered on the sides of stocking blanks.

The object of my invention is to overcome this difficulty, and I accomplish my object by the provision of a novel, simple and efficient indicating device for stretching clocks on embroidery frames by the aid of which the several stocking blanks may be readily and uniformly stretched upon their frames by hand so that their lateral heel seams and 45 adjacent reinforced parts shall all bear the same relation to their frames.

With this object in view my invention consists in the novel construction and combinations of parts hereinafter fully described 50 and particularly claimed.

Figure 1 is a plan view of my improved indicating device. Fig. 2 is a plan view of an embroidery frame having a stocking blank stretched thereon. Fig. 3 is a plan view of

the indicating device and the embroidery 55 frame applied thereto. Fig. 4 is a side view of the parts shown in Fig. 3. Fig. 5 is a vertical section, on line 5—5 of Fig. 3.

Referring to the drawings, 2 designates a base board having upwardly-extending supporting blocks 3 secured thereto. The upper faces of the blocks 3 are in the same horizontal plane and they are adapted to receive and support a frame 4 which in turn is adapted to receive the article to be embroidered, the frame 4 shown herein and referred to hereinafter being adapted to receive a stocking blank and being hereinafter referred to as the embroidery frame.

Extending above the upper faces of the 70 supporting blocks 3 outwardly thereof are side stops 6 which are formed of angle irons suitably secured to the base board 2 and which serve to prevent lateral displacement of the embroidery frame 4 when it is placed 75 upon the blocks 3. Endwise displacement of the frame 4 in one direction is prevented by an end stop 7 formed by an angle iron which is secured to the base board 2; and endwise displacement of the frame 4 in the 80 other direction is prevented by flat springs 8 which are secured to an angle iron 9 which in turn is secured to the base board 2.

Upward displacement of the frame 4 adjacent to the springs 8 is prevented by a 85 finger 10 secured to the angle iron 9 and adapted to extend over the frame 4. The embroidery frame 4 is further held firmly in position upon the blocks 3 by a flat spring arm 11, one end of which is pivoted, 90 at 12, to one of the angle pieces 6, and the other or free end of which is adapted to engage one side of the embroidery frame 4 and press the opposite side of the frame 4 firmly against the adjacent stops 6. By 95 drawing the free end of the spring arm 11 away from the frame 4 by hand it may be moved on its pivot 12 downwardly below the frame 4 to an inoperative position, and upwardly from its inoperative position to 100 an operative position adjacent to the side of the frame 4. Upward movement of the arm 11 is limited by a stop pin 13 on the angle iron 6, and downward movement of the arm 11 is limited by the base board 2. 105

Extending between and secured to the stops or angle irons 6 on the respective sides of the base board 2 are two screw-

threaded rods 14 which are adapted to support two thin parallel plates 15 having openings in the ends thereof through which the rods 14 extend. The plates 15 are held 5 in the position shown by nuts 16 screwed on to the rods 14 and engaging the sides of the plates 15. By adjusting the nuts 16, the plates 15 may be adjusted toward or from each other, as desired. The upper 10 horizontal edges of the plates 15 are in the same horizontal plane with the upper faces of the supporting blocks 3, or substantially so, and they form a means for indicating the positions of parts of a stocking 15 blank when held in a predetermined position relatively to the embroidery frame 4, as will be hereinafter described. The plates 15 are provided with upwardly extending pointed pins 17 adapted to penetrate a 20 stocking blank and to indicate the positions of parts thereof relatively to the embroidery frame 4, as will be hereinafter described.

Hinged, at 18, on the stop or angle iron 7 is a plate 19 which is adapted to lie flat 25 upon the embroidery frame 4 when it is supported on the blocks 3, as shown in Figs. 3 and 4, and which is adapted to be moved upwardly and outwardly on its hinge 18 to permit a frame 4 to be placed upon or 30 removed from the supporting blocks 3. This plate 19 is provided with two edges 20 which diverge outwardly from the pins 17, when the plate 19 is in the position shown and which are adapted to indicate 35 the positions of certain lines on the stocking blank relatively to the embroidery frame 4, as will be hereinafter described.

The embroidery frame 4 is formed of 40 sheet metal and comprises parallel side members 21 and parallel end members 22, forming a rectangular frame, as shown, the side members 21 having narrow portions 23 which provide spaces 40 over which certain parts of the stocking blanks are 45 stretched to be embroidered. The inner edges of the side members 21, including the narrow portions 23 thereof, are bent upwardly and are provided with outwardly-extending pointed pins 24, as shown, adapted 50 to receive and retain a stocking blank when stretched upon the frame 4. Each end member 22 has a groove 25 formed therein adapted to receive a clamping bar 26, one 55 end of which is pivoted, at 27, to the end member 22. Each bar 26 is surrounded by a rubber tube or cushion 28 which is adapted to engage a stocking blank and force it into the groove 25 and clamp the blank therein when the blank is placed between 60 the end member 22 and the bar 26, and the bar 26 is moved on its hinge 27 down into the groove 25. The free end of each bar 26 is held in the clamping position within the groove 25 by a spring arm 29 pivoted on 65 the end member 22 and adapted to be moved

over the free end of the bar 26 and under a bracket or arm 30 secured on the end member 22. By moving the arm 26 on its pivot from the position over the bar 26, the bar 26 may be raised on its pivot 27 to 70 release the stocking blank.

The operation is as follows: The spring arm 11 is moved down on its pivot 12 against the base board 2 and the plate 19 is moved on its hinge 18 upwardly and outwardly 75 from the position shown. An embroidery frame 4 is then placed by hand upon the supporting blocks 3 between the side stops 6, and with one end of the frame 4 inserted beneath the finger 10. This end of the frame 4 80 is then pressed against the springs 8 until the other end of the frame may be and is lowered adjacent to the end stop 7. The hand pressure is then removed from the frame 4 and the springs 8 hold the frame 85 firmly against the end stop 7. The spring arm 11 is then raised by hand into engagement with one side member 21 of the frame 4 and thus assists in firmly holding the frame in the desired position upon the blocks 90 95 100 105 110 115 120 125 130

The next step is to apply a stocking blank to the embroidery frame, and I shall first describe the blank which is illustrated, at 31, in Fig. 2. This blank 31 comprises a leg portion 32 a foot portion 33, a toe portion 34 and lateral heel portions 35 and is of usual and well known construction. The toe portion 34 the sides 36 of the foot portion 33 the heel portions 35 and the sides 37 of the leg portion 32 directly above the heel portions 35 are reinforced or made heavier than the remaining portions of the blank 31, so that when the sides of the blank are sewed together to form a stocking, the toe, the bottom of the foot, the heel and the back of the leg, directly above the heel, will be reinforced, as is well known. These reinforced parts of the blank provide the parallel lines 38 at the sides of the stocking at the junction of the reinforced parts with the non-reinforced parts; and when the heel portions 35 of the stocking blank are formed, parts thereof are sewed together, forming side seams which provide visible lines 39 which diverge from the lines 38, as shown. When designs, such as clocks are embroidered on stocking blanks, they are embroidered thereon in a particular relation to the lines 38 and 39; and, therefore, it is necessary that the blanks 31 be stretched upon the frames 4 with their lines 38 and 39 in a predetermined relation to each other and to the embroidery frame 4, so that the stocking blank may be held in the embroidery machine by the frame 4 with the parts of the stocking blank in the proper relation to the embroidery mechanism. When the embroidery frame 4 is placed upon the supporting blocks 3, the upper edges of the plates 15 indicate the positions of the lines 38 of the 130

stocking blank 31, the pins 17 indicate the junction points of the lines 38 and lines 39, and the diverging edges 20 of the plate 19, after it is moved back to the position shown, 5 indicate the positions of the diverging lines 39 of the blank 31, when properly stretched upon the frame 4. After the embroidery frame 4 has been placed upon the blocks 3, as previously described, and before the 10 hinged plate 19 is returned to the position shown, a stocking blank 31 is placed over the frame 4 and the pins 17 are caused to penetrate the junction points between the lines 38 and the lines 39. The operation of 15 placing the stocking blank 31 upon the embroidery frame 4 is all done by hand, and the next step is to stretch the blank 31 longitudinally and clamp the leg portion 32 and the foot portion 34 beneath the clamp bars 20 25 26 at the ends of the frame 4, as shown in Fig. 1. The stocking blank 31 is then stretched laterally and the side portions thereof are impaled upon the outwardly-projecting pins 24, which retain the blank 31 in its stretched condition. The front of the 30 leg portion 32 and the top of the foot portion 33 of the blank, not being reinforced are sufficiently transparent to permit the operator to see the plates 15 through them, and, 35 therefore, the operator, in stretching the blank 31 laterally and impaling the edges thereof on the pins 24, does so in a manner to cause the lines 38 to lie directly above and parallel to the upper edges of the indicating plates 15. Having stretched the blank 31 upon the frame 4 with the lines 38 in proper 40 registry with the indicating plates 15, the indicating plate 19 is moved on its hinge 18 back to its operative position shown in the drawings, over the toe and foot portions 34 and 33 of the blank 31. The blank is then 45 readjusted on the impaling pins 24 until the lines 39 of the blank are directly beneath and parallel to the diverging edges 20 of the plate 19. It is necessary to have the indicating means for the positions of the lines 39 above the stocking blank, because the reinforced heel portions 35 of the blank are not 50 sufficiently transparent to permit the operator readily to see through them. After a stocking blank 31 has been thus stretched upon a frame 4, the plate 19 is raised on its hinge and moved outwardly to its inoperative position, the spring arm 11 is lowered 55 from the frame 4, the frame 4 is removed from the blocks 3, another embroidery frame is placed upon the blocks 3 and the operation just described is repeated in stretching another stocking blank on the substituted 60 embroidery frame.

I claim:

1. A device for the purpose set forth, comprising a base portion, means on the base portion for indicating the positions of 65 parts of a stocking blank when held in a

predetermined position on an embroidery frame, means on the base portion to support an embroidery frame in a predetermined position relatively to and extending around said indicating means and means to prevent displacement of said frame relatively to said supporting means.

2. A device for the purpose set forth, comprising a base portion, means on the base portion for indicating the positions of parts 70 of a stocking blank when held in a predetermined position on an embroidery frame, means on the base portion to hold an embroidery frame in a predetermined position relatively to and extending around said indicating means, and pointed pins extending 75 upwardly from said indicating means and adapted to penetrate a stocking blank placed over the same.

3. A device for the purpose set forth, comprising a base portion, means on the base portion for indicating the positions of parts 80 of a stocking blank when held in a predetermined position on an embroidery frame, blocks extending upwardly from the base 85 portion and adapted to support an embroidery frame in a predetermined position relatively to and extending around said indicating means, side stops adapted to prevent lateral displacement of an embroidery frame 90 when supported on said blocks, and end stops adapted to prevent longitudinal displacement of an embroidery frame when 95 supported on said blocks.

4. A device for the purpose set forth, comprising a base portion, means on the base portion for indicating the positions of parts 100 of a stocking blank when held in a predetermined position on an embroidery frame, blocks extending upwardly from the base 105 portion and adapted to support an embroidery frame in a predetermined position relatively to and extending around said indicating means, stops adapted to prevent displacement of an embroidery frame when 110 supported on said blocks, and a spring adapted to press an embroidery frame against one of said stops when said frame is supported on said blocks.

5. A device for the purpose set forth, comprising a base portion, means on the base portion for indicating the positions of parts 115 of a stocking blank when held in a predetermined position on an embroidery frame, blocks extending upwardly from the base 120 portion and adapted to support an embroidery frame in a predetermined position relatively to and extending around said indicating means, stops adapted to prevent displacement of an embroidery frame when 125 supported on said blocks, and a pivoted spring movable into and from an operative position adapted to press an embroidery frame against one of said stops when said frame is supported on said blocks.

6. A device for the purpose set forth, comprising a base portion, means on the base portion to hold an embroidery frame in a predetermined position, and a member mounted on the base portion and movable into and from an operative position above the space within an embroidery frame supported by said means, said member having indicating portions which when said member is in the operative position indicate the positions of parts of a stocking blank when said blank is held in a predetermined position on an embroidery frame supported by said means.
- 15 7. A device for the purpose set forth, comprising a base portion, means on the base portion to hold an embroidery frame in a predetermined position, a member mounted on the base portion and movable into and from an operative position above the space within an embroidery frame supported by said means, said member having indicating portions which when said member is in the operative position indicate the positions of parts of a stocking blank when said blank is held in a predetermined position on an embroidery frame supported by said means,
- 20 25

and means on the base portion beneath the plane of said member when in the operative position for indicating the positions of other parts of said stocking blank when held in its said position.

8. A device for the purpose set forth, comprising a base portion, means on the base portion to hold an embroidery frame in a predetermined position, a member mounted on the base portion and movable into and from an operative position above the space within an embroidery frame supported by said means, said member having indicating portions which when said member is in the operative position indicate the positions of parts of a stocking blank when said blank is held in a predetermined position on an embroidery frame supported by said means, and pointed pins extending upwardly from the last named means and adapted to penetrate a stocking blank placed over the same.

In testimony whereof I affix my signature in presence of two witnesses.

LEON KLEIN.
